United States Patent Office

Des. 203,778
Patented Feb. 15, 1966

203,778

PORTABLE SPRAY PAINTING UNIT

Henry R. Johannes, Royal Oak, Mich., assignor to The DeVilbiss Company, Toledo, Ohio, a corporation of Ohio

Filed Dec. 4, 1964, Ser. No. 82,915

Term of patent 14 years

(Cl. D65—1)

FIG-4-

FIG-5-

FIG-6-

FIGURE 1 is a perspective view of a portable spray painting unit embodying my new design;

FIGURE 2 is a front elevational view;

FIGURE 3 is a rear elevational view;

FIGURE 4 is a top plan view;

FIGURE 5 is a side elevational view taken from the front side of the unit as shown in FIG. 1; and

FIGURE 6 is a side elevational view of the opposite side.

I claim:

The ornamental design for a portable spray painting unit, substantially as shown.
